UNITED STATES PATENT OFFICE

169,303

FISH LURE

Wyatt Wagner Dawson, Arlington, Va.

Application November 25, 1952, Serial No. 22,440

Term of patent 7 years

(Cl. D31—4)

To all whom it may concern:

Be it known that I, Wyatt Wagner Dawson, a citizen of the United States, residing at 2701 16th Street South, in the county of Arlington and State of Virginia, have invented a new, original, and ornamental Design for a Fish Lure, of which the following is a specification, reference being had to the accompanying drawing, forming a part hereof.

Fig. 1 is a side elevational view of a fish lure showing my new design.

Fig. 2 is a top plan view thereof.

I claim:

The ornamental design for a fish lure, as shown.

WYATT WAGNER DAWSON.
